CONTROL APPARATUS FOR AUTOMATIC PHONOGRAHS

Ralph R. Erbe, Fort Wayne, Ind., assignor to The Capehart Corporation, Fort Wayne, Ind., a corporation

Application March 28, 1935, Serial No. 13,387

9 Claims. (Cl. 194—15)

This invention relates to control apparatus for an automatic phonograph of the record-changing type. The apparatus is particularly adapted to coin controlled phonographs of the selective type, but certain features of the invention are applicable to non-selective phonographs and to phonographs with which coin control is not desired. By "selective type" is meant a phonograph in which a number of records are stored 5 in a magazine, any one of which may be removed therefrom and played at the will of the operator.

One object of the invention is to provide a coin control which may accept coins of several 15 denominations and will cause the phonograph to play a predetermined number of selections, depending upon the value of the coins received.

Another object of the invention is to provide selecting means by which the entire number of 20 selections corresponding to the coins inserted may be chosen at one time.

Another object of the invention is to provide means by which the number of selections played for a coin of a given value may be changed at 25 will by the owner of the machine.

The features by means of which these and other objects are accomplished will be apparent from the accompanying drawings and the following description and claims:

30 Fig. 1 is a wiring diagram of the electrical connections as used in carrying out the invention in a preferred form. Fig. 2 is a sectional view of a switch used for selecting the record or records to be played and for initiating the operation of the phonograph. Fig. 3 is an elevational view of the same. Fig. 4 is a plan view of a portion of one of the counting devices used with the apparatus. Fig. 5 is an elevational view on the line 5—5 of Fig. 4. Fig. 6 is an alternative form of wiring 35 for a non-coin-operated phonograph. Fig. 7 is another alternative form for a coin-operated non-selective phonograph.

In the preferred form of the invention shown 45 in the drawings, the principal elements indicated by name in Fig. 1 are the phonograph proper, the amplifier and speaker, the cabinet selector switch which may be mounted on the cabinet of the phonograph, the cabinet coin chutes which may 50 also be mounted on or within the cabinet, the selection counter, the play counter, the price changer and a remote control station. Each of these elements will be described in detail before describing their interconnection and joint operation.

Phonograph

The apparatus is particularly adapted to be used with the selective type of phonograph disclosed in my copending application, Serial No. 10,441, filed March 11, 1935. This type of phonograph is provided with a plurality of solenoids 10, each of which, when momentarily actuated, sets a mechanism which selects a record in the magazine to be played. As described in said copending application, said mechanism is such that when several of said solenoids are simultaneously actuated, the corresponding records will be played at successive operations of the phonograph. The phonograph is also provided with an electric motor 11 which drives the usual playing turntable and which also drives the record-changing mechanism. The record-changing mechanism may be that shown in the before mentioned copending application or any other well known form which automatically removes a record from the turntable upon completion of playing, returns it to the magazine, moves another record from the magazine to the turntable and starts the playing of the same. Such record-changing mechanisms invariably include 20 a shaft known as the "one-revolution shaft", which makes a complete revolution during the record-changing cycle and which comes to rest during the playing of the record. The said shaft is indicated diagrammatically in the drawings at 25 12 and carries a cam 13 which is adapted at one point in its revolution to close momentarily a pair of contact members 14. This operation may occur at any time during the record-changing cycle but preferably immediately or soon after the playing of a record is completed. The closing of said contact stops the operation of the motor by circuits to be hereinafter described unless further selections have been paid for and selected.

Amplifier and speaker

The amplifier and speaker may be of any well known form and are electrically connected to 45 the pickup mechanism of the phonograph by any well known means not shown in the diagram.

Cabinet selector switch

The cabinet selector switch is shown diagrammatically in Fig. 1 and in section in Fig. 2 while Fig. 3 shows an elevational view of the same. The switch includes a base 15 of insulation material which may be mounted by screws 16 on the phonograph cabinet 17. A plurality of contact 50 55

buttons 18 corresponding in number to the number of records in the phonograph magazine are set into the base 15 and are arranged in a circle, as shown in Fig. 1. Each of these contact buttons is connected by a wire 19 with the corresponding solenoid 10 in the phonograph mechanism. A metallic bushing 20 is mounted in the center of the base 15 and slidably supports a stem 21 carrying at its outer end a knob 22 and a dial 23. The dial 23 has secured to the inner surface thereof a resilient finger 24 adapted to successively engage the buttons 18 as the dial is rotated by the knob 22. The dial 23 carries a series of index numbers shown in Fig. 3 corresponding to a printed list of selections which may be mounted in any convenient place on the cabinet. The dial may be arranged so that when each figure is uppermost on the dial, the finger 24 engages the button 18 connected to the sole-
20 noid 10 corresponding to the selection in the phonograph magazine represented by that figure.

A compression spring 25 surrounds the stem 21 abutting against the end of the bushing 20 and against the finger 24 and normally urges the stem to the right in Fig. 2. Movement of the stem to the right is limited by a pin 26 engaging the end of the bushing 20. The stem 21 carries at its inner end a contact tip 27 adapted to engage a contact tip 28 carried by a metallic yoke 29 supported upon the back of the base 15. Contact between the point 27 and the point 28 is made by pressing the knob 22 against the action of the spring 25. A wire 30 is connected to the yoke 29 and a wire 31 is connected by means of a washer 32 to the bushing 20 and is thus electrically connected to the stem 21, point 27 and to the contact finger 24.

Cabinet coin chutes

40 The cabinet coin chutes are shown diagrammatically in Fig. 1. In the drawings three chutes are shown, one marked 25¢, one marked 10¢ and one marked 5¢, each of which is adapted to receive a coin of the indicated denomination. 45 The 5¢ chute is arranged so that a coin dropped therein momentarily closes a pair of electrical contact members 33. Similarly, a coin dropped in the 10¢ chute closes a pair of contact members 34. A coin dropped in the 25¢ chute first momentarily closes a pair of contact members 35 and thereafter a second pair of contact members 36. These chutes may be of any type well known in the art and for that reason are not described herein in more detail.

Selection counter

60 The selection counter is diagrammatically shown in Fig. 1 and portions thereof are shown in detail in Figs. 4 and 5. The counter is provided with a gear wheel 37 freely mounted for rotation about a vertical axis 38. Grouped about the gear 37 there are a plurality of counting units indicated by the numbers 39A, 39B, 39C and 39D, each of which is constructed substantially as shown in Fig. 4. Each counting unit consists of a solenoid coil 40 carried upon a stationary sleeve 41 which is in turn supported upon a post 42. An armature 43 is slidably mounted in the sleeve 41 and is moved to the left in Fig. 4 when the solenoid 40 is energized. A pin 44 carried upon one end of the armature 43 has connected thereto a tension spring 45 connected at its opposite end to the post 42. The spring 45 thus normally urges the armature 43 to the right.

Pivotedly connected to the armature 43 by means of the pin 44 there is a ratchet member 46 formed with upper and lower portions engaging the upper and lower surfaces of the gear 37 and thus preventing rotation of the armature 5 15 43. The ratchet member 46 is also provided with a vertical operating edge 47 adapted to engage the teeth of the gear 37 when the armature is moved to the left. The ratchet member is normally urged toward the gear 37 by a torsion 10 spring 48.

In the normal position of the device with the solenoid 40 deenergized, the spring 45 holds the ratchet member 46 flush against the end of the sleeve 41. In this position, the edge 47 of said member is withdrawn from the path of travel of the gear and thus cannot interfere with the movement of the gear in either direction. When the solenoid is energized, however, to move the armature to the left, the ratchet member is moved about its pivotal mounting by the spring 48, bringing the operating edge 47 into engagement with the gear teeth and rotating the gear until the ratchet member strikes an adjustable stop 49. When the solenoid is again deenergized, the spring 45 draws the ratchet member backward and it slides freely over the gear teeth. A finger 50 resiliently engages the gear between its teeth to prevent accidental rotation thereof and to prevent backward movement of the gear 30 in the backward movement of the ratchet member. The pressure of member 50, however, is not sufficient to prevent the forward movement of the gear when positively actuated by the solenoid.

55 In Fig. 1, the four solenoids for the four counting units are indicated respectively by the reference numerals 40A, 40B, 40C and 40D and the corresponding stop members are indicated by the reference numbers 49A, 49B, 49C and 49D. The 40 counting units 39A, 39B and 39C move the gear in a counterclockwise direction while the counting unit 39D moves the gear in the clockwise direction. The stop 49A is placed to permit the gear to be moved by its corresponding counter 45 through the space of one tooth only. The stop 49B is placed to permit its counting unit to move the gear through the space of two teeth. The stop 49C is located to permit its counter to move the gear through the space of five teeth and the stop 49D is located to permit a movement of one tooth in the opposite direction.

60 The gear 37 carries an arm 51 adapted to break the contact between a pair of contact members 52 when the gear has been moved to a predetermined position. This predetermined position is assumed when the phonograph is at rest and no coins have been deposited in the coin slot. When a coin has been deposited, one or more of the solenoids 40A, 40B or 40C, depending upon the value of the coin, is energized, moving the gear counterclockwise a predetermined number of teeth and freeing the arm 51 from the contacts 52 and permitting the latter to become electrically engaged. If now the solenoid 40D is momentarily energized a number of times equal to the number of teeth through which the gear has been moved, the arm 51 is brought back to engage and open the contactors 52.

65 The armature 43 of the counting unit 39D carries an insulated pin 53 engaging one of a pair of contact members 54 when the solenoid 40 is deenergized and maintaining said contact members out of engagement with each other. When the solenoid 40 is energized and the said arm- 70

75

ture moved to the left, the contact members 54 are closed for a purpose to be hereinafter described.

Play counter

5 The play counter is a control box of a well known form in common use with automatic phonographs. It includes a ratchet wheel 55 normally urged in a counterclockwise direction by a torsion spring 56. A solenoid 57 having an armature 58 connected to a link 59, when energized, draws said link to the right to cause a tooth 60 thereon to engage the ratchet wheel 55 and move the same clockwise through a distance of one tooth. An escapement lever 61 normally prevents return rotation of the ratchet wheel but permits it to return through a distance of one tooth when a pair of magnets 62 are momentarily energized to attract and then release the lever 61. Thus, the ratchet wheel is moved one tooth in one direction when solenoid 57 is energized and one tooth in the opposite direction when the magnet 62 is energized.

The ratchet wheel 55 carries a pin 63 adapted to engage the end of a pivoted lever 64 which carries a contact member 65 at one end. The contact member 65 normally engages a contact finger 66. It will be apparent that when the magnets 62 have been energized a sufficient number of times, the pin 63 will engage the lever 64 and will move the same to break contact between the members 65 and 66. Thereafter, if the solenoid 57 is energized, the pin 63 will release the lever 64 and permit contact to again be made between the contact members 65 and 66. In order to again break the contact, the magnets 62 must be energized once for each time that the solenoid 57 has been energized.

Price changer

40 The price changer consists of a base carrying a pair of jacks 67 electrically connected together, a pair of jacks 68 connected to each other and a single jack 69, together with a plurality of plugs 70, 71, 72 and 73 each of which may be inserted in any one of the jacks. The price changer is, of course, located in some position where it is accessible only to the owner of the machine and not to the operator. This is preferably within the cabinet and the cabinet is preferably provided with a suitable lock.

Wiring and operation

The power for operation is preferably supplied from the usual household receptacle by means of a plug 74 attached to a cable 75 leading to a fuse block 76 having the usual pair of fuses 77 mounted thereon. A power main 78 leads from one of the fuses 77 to one terminal of the motor 11, to the amplifier and speaker, to one terminal of the primary winding of a transformer 80 and to one of the contact members 14 in the phonograph. A second power main 81 has branches leading to the second of the primary winding terminals of the transformer, to the contact member 65 and to one terminal of the solenoid 57. The finger 66 is connected by a power line 82 to the second terminal of the motor 11 and to the amplifier and speaker. When the contact members 65 and 66 are in engagement, the following circuit is completed for energizing the motor 11 and the amplifier and speaker: 78, 79, motor, amplifier and speaker, 82, 66, 65, 81, 78. This circuit is completed and broken by the movement of the lever 64 in the play counter.

The second terminal of the solenoid 57 is connected by a conductor 83 to the second of the contact members 14. At each record-changing operation, the contactors 14 are momentarily closed to energize the solenoid 57 by the following circuit: 78, 79, 14, 83, 57, 81, 78.

The secondary winding of the transformer 80 has connected thereto a pair of distributors 84 and 85, branches of which lead to various electric elements as indicated by the diagram. These 10 distributors furnish low voltage current from the transformer secondary for the operation of the several control circuits. Other conductors shown in the diagram will be referred to only by number in tracing out the circuits of which they 15 form a part.

In describing the operation of the illustrated apparatus it will first be assumed that the machine is to operate to give one selection for 5¢, two for 10¢ and five for 25¢. The plug 73 will 20 then be inserted in one of the jacks 67. The plug 72 will be inserted in one of the jacks 68. The plug 70 will be inserted in the jack 69 and the plug 71 will not be used. If now a 5¢ piece is dropped in the appropriate slot, the contacts 33 25 will be momentarily closed, completing the following control circuit: 80, 35, 33, 86, 73, 67, 87, 40A, 84, 80. This circuit energizes the solenoid 40A and moves the gear 37 counterclockwise one tooth corresponding to the one selection to be 30 played for 5¢. If a 10¢ piece is deposited in the proper chute the contacts 34 are momentarily closed and the following circuit is completed: 80, 35, 34, 88, 72, 68, 89, 40B, 84, 80. This circuit energizes the solenoid 40B to move the gear 37 counterclockwise two teeth corresponding to the two selections to be played for 10¢. If a 25¢ 35 piece is deposited in its proper slot, the contacts 35 will first be momentarily closed, but since these are connected by a conductor 99 to the plug 71 which is not in use, nothing happens. The contacts 36 will then be closed, completing the following circuit: 80, 85, 36, 84, 70, 69, 92, 40C, 84, 80. The solenoid 40C is energized by 40 this circuit and moves the gear 37 counterclockwise five teeth corresponding to the five selections to be played for 25¢. The gear 37 therefore, moves one tooth for each selection that is to be played and this movement is determined by the 45 value of the coins inserted in the slots and by the arrangement of the plugs in jacks 67, 68 and 50 69.

If it is desired to change the price, it is only necessary to shift the plugs 70, 71, 72 and 73 into the proper jacks in the price changer. For example, if it is desired to give six selections for 25¢, the plug 71 is inserted in the second of the jacks 67, the other plugs remaining as before. The insertion of a coin in the 25¢ chute then first energizes the solenoid 40A to move the gear one tooth and then energizes the solenoid 40C to move the gear five teeth. Similarly, seven 55 selections for 25¢ may be secured by placing the plug 71 in one of the 68 jacks. If it is desired to give one selection for 10¢ and three for 25¢, the plug 72 (10¢) is inserted in one of the 67 jacks (one selection), the plug 71 (25¢) is inserted in the second of the 67 jacks (one selection) and the plug 70 (25¢) is inserted in one of the 68 60 jacks (two selections). The 73 plug (5¢) will not be used and the 5¢ coin chute will be rendered inoperable in any well known manner. Thus, many different desired combinations of price may be set up on the price changer and selections will 65 70 75

be delivered accordingly. Obviously, counting units may be adjusted to give three or four or other numbers of selections for a given coin, as well as the one-two-five arrangement shown herein.

When a coin has been inserted in the appropriate chute and the gear 37 moved any number of teeth in the counterclockwise direction, the arm 51 moves to permit the 52 contacts to be closed. This completes a circuit as follows: 80, 10 84, 52, 30, a lamp 93, 85, 80. The lamp 93 is placed to illuminate an opening 94 in the face of the selector switch and the lighting of the lamp by this circuit indicates to the operator 15 that he may now make his selections. The operator may then turn the knob of the selector switch to bring the finger 24 into contact with any of the buttons 18. When the dial indicates the number of a selection he wishes played, he 20 presses the knob 22 and makes contact between the points 27 and 28. This contact completes three circuits,—first: 80, 84, 52, 30, 28, 27, 24, 18, 19, 10, 85, 80. This circuit energizes the appropriate solenoid 10 for selecting a record to be 25 played. Second: 80, 84, 52, 30, 28, 27, 31, 40D, 85, 80. This circuit energizes the solenoid 40D to move the gear 37 one tooth in the clockwise direction. Third: 80, 84, 52, 30, 28, 27, 31, 62, 35, 80. This circuit energizes the magnet 62 to 30 permit the ratchet wheel 55 to move one tooth in the counterclockwise direction. It thus frees the pin 63 from the lever 64 if the pin has not already been freed and permits the engagement of the 65—66 contactors to start the phonograph 35 and to energize the amplifier and speaker. It is apparent that none of these three circuits could be completed if the gear 37 had not been moved to permit closing of the 52 contact. For that reason, operation of the selector switch previous to the deposition of a coin has no effect.

If the coin deposited called for only one selection, the gear 37 was moved only one tooth in the counterclockwise direction. The operation of the selector switch to energize the solenoid 40D, 45 therefore, returns the gear to the normal position, opening the 52 contactors and preventing further effective operation of the selector switch. The opening of these contactors also extinguishes the lamp 93 and indicates that no more selections 50 are available. If the coins deposited call for more than one selection, the 52 contacts remain open until the selector switch has been operated a sufficient number of times to return the arm 51 to its initial position, at which time the 52 contacts will be opened as before. Thus, as many 55 selections as have been paid for may be made on the selector switch before the circuits are broken by the return of the arm 51 to normal position.

Since the operation of the solenoid 40D is 60 relatively rapid, it is possible that the 52 contact might be broken on the last selection before the magnet 62 could be completely energized to operate the play counter. For this reason the contactors 54 are connected in parallel with the 65 contactors 52 and maintain these circuits complete as long as the knob 22 is pressed, even though the 52 contact may be broken. When the operator releases the knob 22, however, the solenoid 40D is deenergized and the 54 contacts are 70 opened, thus breaking the circuits.

Since the magnet 62 is energized each time the selector switch is operated, the pin 63 is moved away from the lever 64 a distance corresponding to the number of selections made. After each 75 selection is played, the solenoid 57 is energized

as previously described to move the pin one space in the clockwise direction and when the proper number of selections have been played, the pin engages the lever 64 and opens the 65—66 contact to stop the phonograph and kill the amplifier and speaker.

Summarizing the operation, it may be said that when a coin or coins are deposited, the selection counter conditions the apparatus for the selection of an appropriate number of records, and the operation of the selector switch then selects the records, operates the selection counter to check off the number of records selected and operates the play counter to condition the apparatus for the playing of the number of records selected, and the operation of the phonograph itself then checks off the records on the play counter as they are played. In a broader sense, it may be said that the selection counter conditions the apparatus for the playing of the number of records paid for, since only the number of records set up on the selection counter may be played.

Remote stations

For remote control of the instrument, there 25 may be provided one or more remote stations, one of which is shown in the diagram Fig. 1. This station is provided with a selector switch 95, a lamp 96 and coin chutes 97 of the same construction as the selector switch, lamp and coin chutes on the cabinet. The conductors leading from the cabinet station are connected to the terminals of suitable sockets marked "Socket A" and "Socket B", which may be mounted on the cabinet. Plugs A and B which may be inserted in the sockets A and B are provided with terminals for corresponding conductors which lead through cables 98 and 99 to the remote station and are there connected to the corresponding elements in the remote station. The remote station is thus connected in parallel with the cabinet 40 station and operates the mechanism in a corresponding fashion. Obviously, as many remote stations may be supplied as are desired.

The foregoing specification describes a preferred form of the invention but it is obvious that many variations may be made therein without departing from the scope of the invention as defined by the appended claims. For example, for home use, the coin apparatus and selection counter may be omitted, only the selector switches on the cabinet and at the remote stations and the play counter being used. The 52 contacts are then bridged or permanently closed and the operator may pre-elect as many records as desired. 45 The number of records selected are checked in on the play counter and checked off as played, the phonograph being stopped when all selected records have been played. A wiring diagram for such operation is shown in Fig. 6 in which parts 60 numbered in the 100 series have the same construction and function as corresponding parts numbered in the unit series in Fig. 1. In this arrangement, the coin chutes, price changer and selection counter with their connections are 65 omitted and the conductor 184 leads directly from the transformer secondary to the contact 128 in the selector switch instead of carrying its circuits through the 52 contacts as before. Remote stations may be used in this arrangement as well 70 as in that of Fig. 1.

For use with the non-selective type of phonograph, the selector switch and play counter are omitted, the 52 contact being used to start the phonograph instead of the 65—66 contact and 75

the 40D solenoid being operated by the 14 contact to check off the played records. The wiring for this purpose is shown in Fig. 7 in which parts numbered in the 200 series have the same construction and function as corresponding parts numbered in the unit series of Fig. 1. In this arrangement, the selector switch and play counter with their connections are omitted, conductors 281 and 282 are connected to the 252 contacts instead of the 65-66 contacts and the 40D solenoid is operated by the 214 contacts by means of the following circuit 280-285-214-293-240D-284-280.

The invention claimed is:

1. Control apparatus for an automatic phonograph having electrically operated means for pre-selecting a plurality of records to be played, said control apparatus including coin receiving means having electric contact elements actuated by the receipt of a coin or coins, electrical elements connected to and controlled by said contact elements, a movable member moved by said electrical elements a predetermined distance from a normal position each time a coin of a certain value is received by said coin receiving means, a manually operable selector switch, electric connections between said switch and the phonograph pre-selecting means by which the latter is actuated to select a record each time said switch is operated, means controlled by said movable member to render said switch ineffective when said member is in said normal position, an electrical element connected to and controlled by said selector switch and operating to move said member a predetermined distance toward said normal position each time said selector switch is operated to select a record, electrical means actuated by said phonograph each time a record is played, and an electrical counting device connected to and controlled by said last mentioned electrical means and by said selector switch and operating to stop the phonograph when as many records have been played as have been selected by operation of said switch.
2. Control apparatus for an automatic phonograph having means for preselecting records to be played, said control apparatus including coin receiving means adapted to receive coins of different denominations and having a plurality of electrical contact elements each of which is actuated by the receipt of a coin of a particular denomination, a movable member, an electrical element connected to and controlled by each of said contact elements, each of said elements moving said movable member away from a normal position a distance proportional to the number of selections to be played in return for a coin of the corresponding denomination, a manually operable selector switch, electric connections between said switch and the phonograph pre-selecting means by which the latter is actuated to select a record each time said switch is operated, means controlled by said movable member to render said switch ineffective when said member is in said normal position, an electrical element connected to and controlled by said selector switch and operating to move said member a predetermined distance toward said normal position each time said selector switch is operated to select a record, electrical means actuated by said phonograph each time a record is played, and an electrical counting device connected to and controlled by said last mentioned electrical means and by said selector switch and operating to stop the phonograph.

graph when as many records have been played as have been selected by operation of said switch.

3. Control apparatus for an automatic phonograph including coin receiving means having a plurality of electrical contact elements successively actuated by receipt of a coin, counting apparatus controlling the playing of the phonograph and including a plurality of electrically operated counting units each adapted when actuated to condition said apparatus for the playing of a different predetermined number of records, and electrical connections between each of said contact elements and a corresponding counting unit by means of which each unit is actuated by the actuation of one of said contact elements, said connections including selective means by which said contact elements may be connected to any of said counting units to alter the number of records played in return for said coin.

4. Control apparatus for an automatic phonograph having means for selecting records to be played, said control apparatus including coin receiving means, a selection counter operated by said coin receiving means and adapted to condition said apparatus for the selection of a predetermined number of records upon receipt of a coin, a play counter, a selector device adapted to operate said record selecting means, to operate said selection counter to check off the records as selected and to operate said play counter to condition the apparatus for the playing of the number of records selected, and a phonograph operated device operating said play counter to check off the records as played, said play counter serving to stop the operation of the phonograph when the selected records have been played and checked off.

5. Control apparatus for an automatic phonograph having means for selecting records to be played, said control apparatus including coin receiving means, a selection counter operated by said coin receiving means and adapted to condition said apparatus for the selection of a predetermined number of records upon receipt of a coin, a play counter, a selector device adapted to operate said record selecting means, to operate said selection counter to check off the records as selected and to operate said play counter to condition the apparatus for the playing of the number of records selected, means controlled by said selection counter to render said selector device ineffective when said predetermined number of records have been checked off, and a phonograph operated device operating said play counter to check off the records as played, said play counter serving to stop the operation of the phonograph when the selected records have been played and checked off.

6. Control apparatus for an automatic phonograph having means for selecting records to be played, said control apparatus including coin receiving means adapted to receive coins of different denominations, a selection counter operated by said coin receiving means and adapted to condition the apparatus for the selection of a predetermined number of records depending upon the value of the coin or coins received, a play counter, a selector device adapted to operate said record selecting means, to operate said selection counter to check off the records as selected and to operate said play counter to condition the apparatus for the playing of the number of records selected, said selector device being ineffective when said predetermined number of records have been checked off, and a phono-

graph operated device operating said play counter to check off the records as played, said play counter serving to stop the operation of the phonograph when the selected records have been 5 played and checked off.

7. Control apparatus for an automatic phonograph having a plurality of electrical selector units each operating when actuated to pre-select a particular record for playing, said control 10 apparatus including coin receiving means, a selection counter operated by said coin receiving means and serving to evaluate the coins received in terms of selections to be played, said counter including an electrically operated check off device, a play counter including electrically operated means for conditioning the apparatus for playing a record, electric circuits for actuating each of said selector units, electric circuits for actuating said check off device and said play 15 counter conditioning means, means for simultaneously completing one of said first mentioned circuits and both of said last mentioned circuits, and means for opening all of said circuits when as many selections as paid for have been made 20 and checked off by said check off device.

8. Control apparatus for an automatic phonograph including a pair of coin receiving units each adapted to receive a coin of a different denomination, an electrical contact element associated with the smaller denominational unit and actuated by the receipt of a coin therein, a pair 25 of electrical contact elements associated with the larger denominational unit and adapted to be successively actuated by the receipt of a coin 30 therein, counting apparatus controlling the playing of the phonograph and including a pair of electrically operated counting units, each adapted when actuated to condition said apparatus for

the playing of a different predetermined number of records, electrical connections between the first mentioned contact element and the counting unit corresponding to the smaller number of records by means of which said counting unit is 5 actuated by actuation of said contact elements, similar electrical connections between one of said second mentioned contact elements and the counting unit for the larger number of records, and similar electrical connections between the 10 other of said second mentioned contact elements and the counting unit for the lower number of records.

9. Control apparatus for an automatic phonograph including a pair of coin receiving units 15 each adapted to receive a coin of a different denomination, an electrical contact element associated with the smaller denominational unit and actuated by the receipt of a coin therein, a pair of electrical contact elements associated with the 20 larger denominational unit and adapted to be successively actuated by the receipt of a coin therein, counting apparatus controlling the playing of the phonograph and including a pair of electrically operated counting units, each adapt- 25 ed when actuated to condition said apparatus for the playing of a different predetermined number of records, electrical connections between the first mentioned contact element and one of said counting units by means of which said 30 counting unit is actuated by actuation of said contact element, a similar electrical connection between one of said second mentioned contact elements and one of said counting units, and a similar electrical connection between the other 35 of said second mentioned contact elements and the other of said counting units.

RALPH R. ERBE.
